(57) **CLAIM**

The ornamental design for a flat spotted dumbbell, as shown and described.

DESCRIPTION

FIG. 1 is a top, front, right side perspective view of a flat spotted dumbbell, showing our new design;

FIG. 2 is a rear view of the flat spotted dumbbell of FIG. 1, showing our new design;

FIG. 3 is a front view of the flat spotted dumbbell of FIG. 1, showing our new design;

FIG. 4 is a left side elevation view of the flat spotted dumbbell of FIG. 1;

FIG. 5 is a right side elevation view of the flat spotted dumbbell of FIG. 1;

FIG. 6 is a bottom plan view of the flat spotted dumbbell of FIG. 1;

FIG. 7 is a top plan view of the flat spotted dumbbell of FIG. 1; and,

FIG. 8 is a view of the flat spotted dumbbell of FIG. 1, and showing appearance in one mode of use where an adult user (shown in broken lines) is shown in one position gripping a handle disposed between weighted ends of the flat spotted dumbbell of FIG. 1.

The broken lines in the drawings depict portions of the flat spotted dumbbell that form no part of the claimed design.
